[57] CLAIM

The ornamental design for a single device generator transfer box, as shown and described.

DESCRIPTION

FIG. 1 is a perspective view of a single device generator transfer box, showing a circuit breaker switch above the circular utility outlet, and showing two pilot lights to the right of the circuit breaker switch.

FIG. 2 is a front elevation view thereof;

FIG. 3 is a side elevation view thereof;

FIG. 4 is a side elevation view thereof, viewed from the side opposite that depicted in FIG. 3;

FIG. 5 is a end elevation view thereof;

FIG. 6 is a end elevation view thereof, viewed from the end opposite that depicted in FIG. 5; and,

FIG. 7 is a rear elevational view thereof.
